UNITED STATES PATENT OFFICE.

LYALL HARCOURT, OF MAPLEWOOD, NEW JERSEY.

DESIGN FOR A LIGHT GLOBE.

Application filed September 27, 1924. Serial No. 10,910. Term of patent 14 years.

To all whom it may concern:

Be it known that I, LYALL HARCOURT, a citizen of the United States, residing at Maplewood, in the county of Essex and State of New Jersey, have invented a new, original, and ornamental Design for Light Globes, of which the following is a specification, reference being had to the accompanying drawings, forming a part thereof, wherein is shown a front elevation of the new design.

The lines of the globe are regular, flowing one into the other on regular curves. From

the greatest diameter of the globe, upwardly, the globe is contracted in the form of a double or ogee curve, and downward the contraction is convex gradual and uniform to provide a continuously convex outer surface. The stippling does not represent ornamentation, the surface of the globe being smooth and uniform.

I claim:

The ornamental design for a light globe as shown and described.

LYALL HARCOURT.
